[57] CLAIM

The ornamental design for a bottle, substantially as shown and described.

DESCRIPTION

FIG. 1 is an elevational view of a bottle showing my new design, the opposite side being the same in appearance;

FIG. 2 is an elevational view looking from the right of FIG. 1, the opposite side being the same in appearance;

FIG. 3 is a top plan view; and

FIG. 4 is a top perspective view thereof.
